UNITED STATES PATENT OFFICE.

HERBERT SCHOLFIELD, OF LOS ANGELES, CALIFORNIA.

BUILDING BOARD.

Application filed May 9, 1921. Serial No. 468,060.

To all whom it may concern:

Be it known that I, HERBERT SCHOLFIELD, a citizen of the United States, residing at Los Angeles, in the county of Los Angeles, 5 State of California, have invented new and useful Improvements in Building Board, of which the following is a specification.

My invention relates to building board, and is especially designed to be secured to 10 the frame work of a building to serve as an outside wall or siding therefor, as well as to provide a lathing surface to which a finish coating of cement or plaster may be applied; said board being so constructed that 15 it may be quickly and easily applied and will form an adequate insulation from the effects of heat, cold and moisture.

Other objects will be apparent from the following description, will be pointed out 20 in the claims and will be embodied in the accompanying drawings, in which:

Fig. 1 represents a face view of a building board panel constructed in accordance with my invention.

25 Fig. 2 is an enlarged vertical section through a portion of the same.

Fig. 3 is an enlargement of a fragment of Fig. 2 showing more clearly certain details of construction.

30 Fig. 4 is a perspective view of one of the binding members, showing its application to some of the structural units which are illustrated in dotted lines.

Fig. 5 is a view similar to Fig. 3 showing 35 a modified form of the building board.

In carrying out my invention 10 represents a building board panel of any desired length and width, which comprises an outer wall 11 and an inner wall 12, spaced apart 40 and held in such spaced relation by means of a plurality of tie and spacing members 13.

The outer wall 10 comprises a plurality of vertically disposed wires or rods 14 which are spaced equally apart in parallel relation 45 and having resting upon their outwardly disposed surfaces a metallic lathing 15 formed of woven wire or expanded metal.

The inner wall 12 comprises a plurality of 50 horizontally disposed rods or wires 16 spaced apart in parallel relation, a sheet of building paper 17 disposed on one side thereof, and an outer sheet of asphaltum 18 disposed on the opposite side thereof, which are secured together by a filling of pitch 19 55 interposed therebetween and encompassing said wires.

The tie and spacing members 13 are preferably formed of a wire which is twisted to form a loop 20 at one of the ends through which the wires 16 pass, a loop 21 adjacent 60 its opposite end through which the wires 14 pass, and an intermediate spacing loop 22. The ends 23 of the wire forming the member 13 extend beyond the loop 21 and serve when twisted together to bind the metallic 65 lathing 15 to the rods or wires 14 as clearly shown in the several figures of the drawing.

By the above recited construction it will be seen that I have provided a building board composed of two oppositely disposed 70 walls spaced apart, one of said walls 12 adapted to rest against the studding of the building, and being formed of insulating material, and the other wall 11 being formed of a lathing to which an outer surfacing and 75 finishing material of cement or the like, may be readily applied after the boards have been secured in place. In order that strength and body may be given to the board, I propose to fill the space between the walls 11 80 and 12 with plaster or cement 24; this may be done during the process of manufacture of the board previous to its being applied to the building as shown in Figs. 1, 2 and 3 of the drawings; or the board may be initially prepared as shown in Fig. 5 of the drawings and the plaster or cement filling 24 applied during the process of applying the board, and if so desired, may be omitted entirely from the construction. 85

The asphaltum sheet 18 is preferably of larger area than the body of the panel 10 and is adapted to extend beyond said body portion adjacent two of its joining edges as shown in Fig. 1 of the drawings, in order 90 that an overlapping at the joint between the panels may be had, when they are placed in position on the building, and the lathing material 15 is also arranged to overlap the body of said panel at two of its adjoining 95 edges for the same purpose.

In order that the plaster filling 24 may be reenforced when in a plastic condition, and to prevent the breaking of the panel when the plaster is in such plastic condition, 100 I place a plurality of strips of building paper 25 under each of the wires or rods 14, thus the panels may be conveniently handled before the plaster has become thoroughly dried, without injuring the same. 110

What I claim is:

1. A building board, comprising a pair

of oppositely disposed walls, one of said walls forming a lathing surface and the other of said walls being formed of an insulating material, means for holding said walls together in spaced relation, and a plastic filling completely filling the space between said walls.

2. A building board, comprising a pair of oppositely disposed walls, each of said walls being composed of a plurality of wires arranged in parallel relation, the wires of one of said walls being embedded between an insulating material and the wires of the other wall being provided with a lathing surface, means for securing said walls together in spaced relation, and a plastic filling completely filling the space between said walls.

3. A building board, comprising a pair of oppositely disposed walls, each of said walls being composed of a plurality of wires arranged in parallel relation, the wires of one of said walls being interposed between sheets of insulating material bound together, the wires of the other wall having secured

thereto a metallic lathing, a plurality of binding members adapted to bind said walls together in spaced relation, and a plastic material completely filling the space between said walls.

4. A building board, comprising a pair of oppositely disposed walls, each of said walls being composed of a plurality of wires arranged in parallel relation, the wires of one of said walls running in one direction and of the other wall in the opposite direction, a plurality of binding members secured to said walls and adapted to hold them apart in spaced relation, a woven wire lathing material secured to one of said walls and the wires of the other wall being interposed between a sheet of building paper and a sheet of asphaltum, a tar pitch material filling between said sheets for embedding said wall wires, and a plaster filling interposed between said walls.

In witness that I claim the foregoing I have hereunto subscribed my name this 15th day of April, 1921.

HERBERT SCHOLFIELD
